CLAIM

The ornamental design for a container for liquid and granular substances, as shown and described.

DESCRIPTION

FIG. 1 is a perspective view of a container for liquid and granular substances incorporating the invention;

FIG. 2 is a front elevation of the container for liquid and granular substances, the rear elevation is a mirror image thereto;

FIG. 3 is a top view of FIG. 1;

FIG. 4 is a bottom view of FIG. 1;

FIG. 5 is a view of the right hand side of FIG. 2; and, FIG. 6 is a view of the left hand side of FIG. 2.

The broken lines in the drawings are for illustrative purposes only and do not form part of the claimed design.
